UNITED STATES PATENT OFFICE

2,575,894

AIR CIRCULATING APPARATUS

John I. Shireman, Hershey, Pa.

Application April 9, 1948, Serial No. 20,069

1 Claim. (Cl. 257—171)

1

This invention relates to an improved air circulating apparatus adapted for use in dwellings and other enclosures in conjunction with either a heating or refrigerating unit for circulating either hot or cold air through the enclosure.

More particularly, it is an object of the present invention to provide an air circulating apparatus including a casing through which the air is propelled and containing a series of horizontal conduits through which all of the air is passed and which conduits are disposed to be either heated or cooled for thereby either heating or cooling the air passing through the unit.

Various other objects and advantages of the invention will hereinafter become more fully apparent from the following description of the drawing, illustrating a presently preferred embodiment thereof, and wherein:

Figure 1 is a side elevational view, partly in section showing the air circulating apparatus employed with the heating unit;

Figure 2 is an end elevational view thereof looking from right to left of Figure 1;

Figure 3 is a top plan view of the apparatus, and

Figure 4 is a fragmentary vertical sectional view showing the apparatus utilized as a cooling and air conditioning device.

Referring more specifically to the drawing, the air circulating apparatus in its entirety is designated generally 5 and includes a relatively wide and relatively tall upright casing 6 adapted to be supported by depending legs 7 and provided with a plurality of spaced horizontal partitions 8 having openings 9 in staggered relationship adjacent opposite ends thereof. The bottom partition 8 forms a chamber or compartment 10 therebelow which, in the embodiment of the invention as illustrated in Figures 1, 2 and 3, is shown containing a suitable burner 11 which is removably disposed therein. One side wall of the casing 6 is provided with an opening normally closed by a door 12 and through which the burner 11 can be applied or removed. The front wall 13 of the casing 6 is provided with one or more openings 14 for admitting air to the chamber 10.

Each of the chambers 15, located between the partitions 8 has a plurality of tubes or pipes 16 extending therethrough from front to rear. Each of the pipes 16 has one end extending through and anchored in the front wall 13 and its opposite end extending through and anchored in the rear wall 17 of the casing 6.

The uppermost partition 8 combines with the

top 18 of the casing 6 to form an upper chamber which communicates with a flue 19 which is connected to and rises from the top 18.

A relatively wide air supply pipe 20 has a portion extending through the chamber 21, formed by the uppermost partition 8 and top 18 and which conduit 20 passes through the front and rear walls 13 and 17 and has an inlet end extending upwardly from adjacent the rear wall 17 and an outlet end extending downwardly adjacent the front wall 13. Said outlet end 22 of the conduit 20 connects with a jacket 23 which is secured to the outer side of the front wall 13 and over the portion thereof through which each of the tubes or pipes 16 extend. An air propelling fan 24 is disposed within the jacket 23 and is adapted to be driven by a motor 25, supported on the conduit portion 22 in a direction for propelling the air from the jacket 23 through the tube 16 toward the rear wall 17 and for drawing the air downwardly through conduit 20 and into said jacket 23.

A relatively large air jacket 26 is secured to and projects from the rear wall 17 and is disposed over a portion thereof through which the tube 16 extends so that all of said tubes will discharge into the jacket 26 which is provided with an outlet conduit extending upwardly from the top thereof as seen at 27 and which may be provided with a plurality of branch conduits, not shown, for distributing the air from the jacket 26 to a plurality of rooms of an enclosure. Likewise, the air conduit 20 may be provided with a plurality of branch conduits leading to separate rooms of an enclosure for drawing air therefrom to the apparatus 5. A trough 28 is disposed in the bottom portion of the jacket 26 and is secured to the rear wall 17 so that the open top thereof will be directly beneath the level of the lowermost tube 16. The trough 28 is provided with a filling spout 29 which extends outwardly from one of the side walls of the jacket 26 and through which said trough may be filled for humidifying the air passing into the jacket 26 from the tube 16.

From the preceding description it will be readily apparent that the products of combustion from the burner 11 will pass upwardly through the openings 9 back and forth by a circuitous route through the compartments or chambers 15 and 21 of the casing 6 for externally heating the tubes 16 so that the air passing through said tubes from the jacket 23 to the jacket 26 will be heated thereby. The products of combustion after being discharged into the upper chamber

21 will pass around a portion of the conduit 20, for heating said conduit portion, and will then be discharged from the casing 6 into the flue 19. It will thus be readily apparent that the apparatus 5 provides an extremely simple and efficient means for heating air and for circulating the heated air to remote portions of an enclosure and for drawing the unheated air from said closure portion through the apparatus to be heated thereby and through the utilization of horizontally disposed tubes which are externally heated by the hot air and products of combustion passing back and forth by a circuitous route upwardly through the casing of the apparatus.

Figure 4 illustrates the apparatus 5 employed as an air conditioner and cooling apparatus and which is readily accomplished by the simple expedient of removing the burner 11 from the chamber 10 and applying a portion of a refrigerating apparatus 30 to said chamber 10 so that the cold air therefrom will chill the tubes 16 for cooling the air drawn through and expelled from the apparatus 5. As illustrated in Figure 4, a portion of the refrigerating apparatus is shown disposed externally of the casing 6 and said portion may be enclosed in a suitable box or other container 31. The apparatus 5 employed with the refrigerating unit 30 is identical in construction to the apparatus as illustrated in Figures 1 to 3 and a further description thereof is therefore considered unnecessary.

Various modifications and changes are contemplated and may obviously be resorted to, without departing from the spirit or scope of the invention as hereinafter defined by the appended claim.

I claim as my invention:

An air circulating apparatus comprising an upright casing, a heating unit mounted in the bottom portion of the casing, partitions forming baffles disposed within the casing above the heating unit and one above the other for directing products of combustion from the heating unit upwardly through the casing by an undulating circuitous route, said casing having a front wall, a rear wall and side walls, a plurality of tubes extending through the casing and opening outwardly of the front and rear walls, said tubes being disposed between the baffles, said baffles having staggered openings located adjacent said side walls for causing the prod-

ucts of combustion to pass back and forth in the casing between the baffles and around the tubes for heating the tubes, a jacket mounted on the outer side of the front wall and communicating with corresponding ends of the tubes, air propelling means disposed in the jacket for discharging air therefrom through the tubes for heating the air, said casing having a top wall spaced from the uppermost baffle, a flue stack rising from said top wall and disposed remote to the opening of the uppermost baffle, an air inlet conduit having a discharge end opening into the jacket, said air inlet conduit having a horizontally disposed enlarged portion extending through the front and rear walls and through the casing between its top wall and the uppermost baffle and substantially filling the upper portion of the casing said enlarged portion of the inlet conduit forming a hollow baffle between the opening of the uppermost baffle and the flue stack around which the products of combustion pass to the flue stack for restricting the discharge of the products of combustion and for initially heating the air passing through the air inlet conduit, and an outlet jacket mounted on the rear casing wall into which each of the tubes discharge and having an outlet conduit leading therefrom for conveying the heated air from the apparatus.

JOHN I. SHIREMAN.
